ELLIPSOGRAPH

Filed May 14, 1929

UNITED STATES PATENT OFFICE

WILLIAM H. HUFF, OF WICHITA, KANSAS

ELLIPSOGRAPH

Application filed May 14, 1929. Serial No. 363,007.

The present invention relates to improvements in drawing instruments and has reference more particularly to a compass for drawing ellipses and ovals of various sizes and proportions in an expeditious and accurate manner.

One of the important objects of the present invention is to provide an ellipsograph wherein means is provided for mechanically controlling the path of movement of a marking member for producing an ellipse or oval with one continuous turn of the instrument.

A further object is to provide an ellipsograph of the above-mentioned character wherein the same includes adjustably connected members, said members being operatively connected together for rotation regardless of their angularly disposed relation with respect to each other.

20 A further object is to provide an ellipsograph of the above-mentioned character which is simple in construction, inexpensive, strong and durable and further well adapted for the purposes for which it is designed.

25 Other objects and advantages of the invention will become apparent from the following description when taken in connection with the accompanying drawings.

In the accompanying drawings wherein 30 like reference characters indicate corresponding parts throughout the same;

Figure 1 is a view partly in elevation and partly in section of the ellipsograph embodying my invention.

35 Figure 2 is a side elevation of the handle portion of the instrument.

Figure 3 is a view similar to Figure 2 looking at right angles thereto.

Figure 4 is a detail sectional view taken 40 approximately on the line 4—4 of Figure 1.

Figure 5 is a similar section taken on the line 5—5 of Figure 1.

Figure 6 is a fragmentary edge elevation 45 of the base showing the gear casing mounted thereon and the connection between the gear casing and the lower end portion of the adjacent leg member.

Figure 7 is a perspective view of an extension arm for association with one of the leg 50 members.

Figure 8 is a detail perspective view of the pen or pencil carrying unit.

Figure 9 is a fragmentary bottom plan view of the base and the gear casing mounted thereon.

Figure 10 is an elevational view of the operating gear members.

Figure 11 is a top plan view thereof;

Figure 12 is a diagram illustrating a portion of the ellipse formed by the use of my 60 improved ellipsograph.

In the drawings wherein for the purpose of illustration is shown the preferred embodiment of my invention, with reference more particularly to the diagram illustrated in 65 Figure 12, the numerals 1 and 2 designate one line while the numerals 3 and 6 designate an intersecting line that is disposed at right angles with respect to the aforementioned line. These lines will constitute the axes 70 upon which the ellipse is to be drawn wherein the ellipse has a major axis one half of which is the distance between 0 located at the point of intersection between said lines, and 2, the minor axis having one half thereof denoted by the distance between 0 and 4. With 0 as the center, the line 0—5 is laid off on line 1—2 equal to the distance between 0 and 4. The distance between 5 and 2 is 75 the difference between the two radii.

Points 2—8—10—12—14—16—18—4—20, etc., are points on the line traced by point 2 and form an ellipse whose minor radius is 0—4 and whose major radius is 0—2.

It is one of the salient objects of the present invention to devise an instrument that will mechanically control the path of either a pencil or pen for producing an ellipse and wherein the pencil or pen will be caused to pass through the point 2—8—10—12—14—90 16—18—4—20, etc., in the manner as described above.

I have therefore devised an improved ellipsograph shown in the accompanying drawings and the description of which will now be 95 specifically described. The numeral 23 designates a metallic base that has arranged on its bottom face the legs 24, which legs space the base plate from the surface of the drawing paper on which the ellipse is to be formed.

Each leg is formed with a socket for receiving a sharp needle point 25 that penetrates the paper for the purpose of preventing any possibility of the instrument slipping or moving 5 after it has been placed in its proper position.

Extending upwardly from the central portion of the base plate 23 is the bolt 26 on which is fixedly secured the spur gear 27, the purpose of which will be presently described. 10 Enclosing the spur gear and mounted for rotation about the bolt 26 is the gear casing 28, the same gradually decreasing in width toward one end and the smaller outer end portion of this gear casing has journaled 15 therethrough the vertically disposed spindle 29 that projects above the top of the gear casing. A pinion 30 is secured on the lower end portion of the spindle 29 for disposition within the gear casing and this pinion 30 20 has meshing engagement with the spur gear 27 in the manner as clearly disclosed in Figure 1. The pinion 30 will revolve about its axis as it is carried around the spur gear 27. Formed on the upper end of the spindle 29 25 is the ball shaped head 31 (Fig. 6) for cooperation with a socket 32 carried by the lower end of a shaft 33 that extends upwardly through a tubular housing 34 constituting a part of one of the leg members of the instrument denoted generally by the numeral 30 35.

The lower end of the tubular member 34 is formed with a fork 36, the furcations of which are disposed on opposite sides of the 35 ball shaped socket 32 and the furcations are pivotally connected to upstanding lugs 37 carried by the outer end portion of the gear casing 28. The pivotal connection between the forked lower end of the tubular member 40 34 and the upstanding spaced lugs 37 is indicated at 38 in Figure 6.

The leg member 35 also includes an upper section consisting of a tubular member 39 and the adjacent ends of the tubular members 45 34 and 39 are formed with complementary forks 40 and 41 respectively that are pivotally connected together in the manner as shown in Figure 5. The upper end of the shaft 33 is formed with a ball shaped head 42 that 50 operates with a socket 43 formed on the lower end of the shaft 44 that rotates within the tubular upper section 39 and the ball and socket connection between the adjacent ends of the shafts 33 and 44 is also clearly illustrated in Figure 5.

Secured on the upper end of the shaft 44 is the cog denoted by the numeral 45 and the teeth 46 of this cog or pinion are cylindrical and crowned with hemispherical caps of 60 equal diameter as disclosed more clearly in Figures 10 and 11, the teeth of the cog being indicated by the reference character 46. The purpose of this particular type of cog or pinion construction will be hereinafter 65 more fully described.

The complementary leg member is denoted generally by the numeral 47 and the same includes an upper tubular section 48, the upper ends of the tubular sections 39 and 48 being pivotally and adjustably connected together within a suitable yoke 49 that is of inverted U-shaped formation and a knurled handle 50 extends upwardly from the crown portion of this yoke for manipulating the instrument when in use. A shaft 51 extends 70 through the tubular member 48 and a cog 52 similar to the cog 45 is carried by the upper end of the shaft 51 for cooperation with the complementary cog 45 and by constructing the teeth of the cog in the manner as shown and above described, said cogs will at all times be in meshing engagement with each other regardless of the angle at which the shafts 44 and 51 are disposed.

The leg member 47 includes an intermediate section 53 that is also of tubular construction and the upper end of the intermediate section 53 is formed with a fork 54. A fork 55 is formed on the lower end of the tubular section 48 and the forks 54 and 55 are pivotally connected together as suggested more clearly in Figure 4 of the drawings. The lower end of the shaft 51 is formed with a socket 56 to receive the ball shaped head 57 formed on the upper end of the short shaft 95 58 that is journaled for rotation within the intermediate tubular section 53 as also shown very clearly in Figure 4. The lower end of the shaft 58 is formed with a slotted head 59 to receive the upper end of the section 60, said 100 section 60 being pivotally connected to the lower end of the shaft 58. The lower end of the shaft 60 is formed with a socket for receiving a pencil carrying unit 61 or a pen carrying unit 62. There is also provided an extension section 63 that may be interposed either between the pen or pencil unit and the section 60 when desired.

The use of my improved ellipsograph is thought to be readily obvious from the construction and description set out above and by substituting the center point formed by the bolt 26 for 0 on the diagram in Figure 12, and point 64 formed by the connection between the section 60 and the slotted head 59 for point 0' in the diagram shown in Figure 12, and the point of the pencil or pen or point 2 in the diagram, the instrument will then be in proper position for forming the desired ellipse with one continuous turn of the instrument and the ellipse formed will be accurate.

It will thus be seen from the foregoing description, that I have provided an instrument for expeditiously and accurately drawing ellipses and ovals of various sizes and proportions, and the simplicity of my instrument enables the parts to be readily and easily adjusted. Furthermore an ellipsograph of the above mentioned character will at all 130

times be positive and efficient in its operation.

While I have shown the preferred embodiment of my invention, it is to be understood that minor changes in the size, shape and arrangement of parts may be resorted to without departing from the spirit of the invention or the scope of the appended claims.

What I claim is:

1. An ellipsograph of the class described comprising a pair of complementary leg members, a base-plate adapted to be fixedly placed on a drawing, means for operatively connecting the lower end of one leg member with the base-plate whereby the leg member will revolve about the base-plate, coacting means between the upper ends of said leg members whereby the same will rotate simultaneously, and a marking element adjustably connected to the lower end of the other leg member as and for the purpose described, each leg member including tubular sections pivotally connected together at their adjacent ends, a shaft disposed for rotation in each tubular section, and a ball and socket connection between the adjacent ends of the shaft in the adjacent tubular sections.

2. An instrument of the class described comprising in combination, a base, means for securing the same on a drawing against movement, a pivot-forming member extending upwardly from the base, a gear mounted on the pivot-forming member in a stationary manner, a pinion meshing with the gear for movement therearound, a casing for the gear and the pinion mounted for pivotal movement on said pivot-forming member, a spindle extending through the gear casing and being fixedly connected with the pinion, a leg member operatively connected at its lower end with the projecting end of the spindle, an additional leg member, means for operatively connecting the upper ends of the leg members together, means connected with the upper end portions of the leg members for manually actuating the first-mentioned leg member to move the same around the stationary gear, and a marking member adjustably carried by the lower end of the second mentioned leg member.

3. An instrument of the class described comprising in combination, a base, means for securing the same on a drawing against movement, a pivot-forming member extending upwardly from the base, a gear mounted on the pivot-forming member in a stationary manner, a pinion meshing with the gear for movement therearound, a casing for the gear and the pinion mounted for pivotal movement on said pivot-forming member, a spindle extending through the gear casing and being fixedly connected with the pinion, a leg member operatively connected at its lower end with the projecting end of the spindle, an additional leg member, means for

operatively connecting the upper ends of the leg members together, means connected with the upper end portions of the leg members for manually actuating the first-mentioned leg member to move the same around the stationary gear, and a marking member adjustably carried by the lower end of the second mentioned leg member, and means for maintaining the operatively connected upper ends of the leg members in any predetermined angular relation with respect to each other.

4. An instrument of the class described comprising in combination, a base, means for securing the same on a drawing against movement, a pivot-forming member extending upwardly from the base, a gear mounted on the pivot-forming member in a stationary manner, a pinion meshing with the gear for movement therearound, a casing for the gear and the pinion mounted for pivotal movement on said pivot-forming member, a spindle extending through the gear casing and fixedly connected with the pinion, primary and secondary leg members, each leg member including sectional tubular members operatively connected together at their adjacent ends, a shaft extending through each tubular section, the adjacent ends of the shaft of each leg member being operatively connected together, the lower end of the lowermost shaft of the primary leg being operatively connected with the projecting end of the spindle for rotation therewith, intermeshing cogs on the upper ends of the uppermost shafts of said leg members, a handle carrying unit supported by the upper connected portions of the primary and secondary leg members for actuating the gear casing and to effect the rotation of said interconnected shafts, and a marking member adjustably connected to the lower end of the secondary leg member.

In testimony whereof I affix my signature.
